FLUORESCENT ALKOXY BENZOYL DERIVATIVES OF 4,4' DIAMINO STILBENE-2,2' DISULFONIC ACID AND DETERGENT COMPOSITIONS CONTAINING SAME

Leslie Noel Savidge, Burton, and Richard Thomas, Bromborough, England, assignors to Lever Brothers Company, Cambridge, Mass., a corporation of Maine

No Drawing. Application March 30, 1948, Serial No. 18,066. In Great Britain April 3, 1947

20 Claims. (Cl. 117—33.5)

1

This invention relates to methods of treating materials with blue-fluorescent substances so as to impart to the materials blue-fluorescent effects, with or without detergents. The invention also relates to new blue-fluorescent agents suitable for use with these methods, including detergent containing compositions.

The present invention is particularly concerned with the treatment of materials, such as, for example, textiles or paper, with fluorescent substances which, without substantially altering the colour of the treated material, are capable of imparting to it a blue fluorescence, that is a fluorescence in which at least a major part of the absorbed ultra-violet light is re-emitted within the blue portion of the spectrum. Substances of this description are herein termed "blue-fluorescent substances."

The characteristic properties of blue-fluorescent substances, namely the absorption of ultra-violet radiations and the re-emission of at least some of the absorbed invisible light as visible light in the form of blue fluorescence, have been made use of for a variety of purposes.

The principal use to which these properties have been put is to the correction or neutralisation of the yellowish or off-white tint of materials such as textile articles, fabric or yarn, or of paper, and so to the improvement of the whiteness of such materials, by incorporating therein blue-fluorescent substances, for example by treating the materials with a dilute aqueous solution or one or more of the substances. The blue fluorescence acquired by the treated materials not only increases the amount of the reflection in the blue region of the spectrum so as to balance the reflection in the yellow region, but the total amount of reflected light is increased by the conversion of invisible ultra-violet light into visible light. The result is to produce an increased total reflection of visible light causing an increased brightness as well as an improved whiteness.

In a similar way it has been proposed to apply blue-fluorescent substances to coloured fabrics for the purpose of intensifying, refreshing or brightening the colour.

It has been proposed to use certain blue-fluorescent compounds to improve the purity or brilliance of the white pattern produced in methods of discharge and resist printing on textiles, by treating the textile at any suitable stage during the printing process with a blue-fluorescent compound, so that the whiteness of the white part of the pattern is enhanced.

It has also been proposed to use blue-fluorescent substances in admixture with a bleaching agent, to give an enhanced whitening effect.

2

It has also been proposed to treat transparent paper, such as regenerated cellulose, with blue-fluorescent substances to produce transparent wrapping materials which will absorb the ultra-violet radiations present in ordinary daylight and which can therefore be used for wrapping food-stuffs and other commodities which are sensitive to ultra-violet light.

Blue-fluorescent substances have been used to impart fluorescence to materials for display, advertising, stage and other decorative purposes, such materials exhibiting one colour or pattern when viewed in ordinary light and another when illuminated by ultra-violet light.

It is also known to incorporate blue-fluorescent substances in textile-marking inks, which when applied in the form of an identification mark to articles to be laundered, will after the completion of the laundering operation, be normally invisible, but when viewed under ultra-violet rays will be brilliantly fluorescent and clearly legible.

Blue-fluorescent substances proposed for use for the above purposes comprise a great number of different organic compounds.

For some purposes it is essential or desirable that the blue-fluorescent substances should have a strong affinity for the material to which they are applied, so that they are not removed when the materials are subsequently rinsed or washed or otherwise treated in aqueous liquids, and numerous blue-fluorescent compounds substantive to textile fibres have been described in the prior art for various industrial applications. Among the compounds proposed as substantive to cellulose are certain di-benzoyl amino-stilbene sulphonic acids and substitution derivatives thereof, in particular diamino derivatives such as, for example 4:4'-di-p-aminobenzoyl amino-stilbene-2:2'-disulphonic acid, or salts thereof.

Other substances consist of stilbene derivatives containing 1:3:5-triazine rings; compounds containing imidazole rings have also been proposed.

The present invention is based on the discovery of new chemical compounds which are substantive and impart fluorescent effects to materials such as textiles or paper; which effects have good stability, not only to air and light, but also to sodium hypochlorite and similar bleaching agents; and the said compounds are therefore particularly useful for imparting fluorescent effects to materials which may be subjected to treatment with hypochlorite or the like. Such treatments are used, for example, in the bleaching of textiles or in the laundering of white articles for improving the colour or removing fruit, tea, coffee and similar stains which are not removed by the normal washing process.

The invention comprises a method of imparting to materials, particularly cotton, linen, rayon and other cellulose materials, blue fluorescent effects by incorporating in the said materials a small proportion of a new compound as described hereinafter. The invention also provides preparations comprising substances such as detergents, starch and other substances, and containing small proportions of the said new compound. In addition, the invention provides methods of incorporating the new compounds in textiles and the like materials, e. g., in the presence of a detergent.

The incorporation of the compounds in textiles and textile articles may be carried out by immersing the articles in an aqueous solution of the compound. It is found, however, that incorporation is often materially assisted by the presence of small percentages (usually quantities below 1% are sufficient) of electrolytes such as sodium carbonate, sodium sulfate or sodium chloride. The process of the invention may advantageously be applied to textiles in any stage of their manufacture or subsequently, that is to say to the yarn, to the newly woven fabric, to new articles made therefrom, or in the washing or rinsing of such articles including soiled articles. As the compounds are substantive to cellulosic textile fibres, the whitening effect produced is of a more or less permanent nature and will survive many ordinary washing or rinsing treatments.

The following substances are illustrative of preferred embodiments for imparting blue fluorescence in accordance with the invention:

Compound A.—Sodium 4:4'-di-p-methoxybenzoylaminostilbene-2:2'-disulfonate:

Compound B.—The ortho-compound corresponding to Compound A:

Compound C.—Sodium 4:4'-di-p-ethoxybenzoylaminostilbene-2:2'-disulfonate:

Compound D.—Sodium 4:4'-di-4''-methoxy-3''-methylbenzoylaminostilbene-2:2'-disulfonate:

Compound E.—Sodium 4:4'-di-3''-acetylaminono-4''-methoxybenzoylaminostilbene-2:2'-disulfonate:

Compound F.—Sodium N:N'-bis-(3''-4''-dimethoxybenzoyl)-4:4'-diaminostilbene-2:2'-disulfonate:

Preparation of the foregoing compounds is illustrated by the following:

Preparation of Compound A.—4:4'-diaminostilbene-2:2'-disulfonic acid (23 g.; 0.062 mol) was stirred and heated with water (150 cc.) and sodium carbonate (5 g.). When the solution boiled, more sodium carbonate was added until the mixture became alkaline. Anisyl chloride (21 g.; 0.124 mol) in pyridine (50 cc.; analytical reagent grade) was added during a period of a few minutes and the mixture heated under reflux for one hour. The liquid was made alkaline once more with sodium carbonate and cooled. The product was collected by filtration, and washed with water until it was a pale orange colour.

15 The material was dissolved in hot aqueous pyridine (80:20; 2.5 litres), decolorised and filtered. On cooling the solution the product was obtained as a pale yellow crystalline powder. This was thoroughly washed with hot water and dried. 20 Yield, 14 g. (approximately 35%).

Preparation of Compound C.—An essential preliminary to the preparation of this compound was the synthesis of the necessary acyl chloride, viz. p-ethoxybenzoyl chloride.

25 *Stage (a).*—*p-Ethoxybenzoic acid.*—p-Hydroxybenzoic acid (14 g.) was dissolved in sodium hydroxide solution (8 g. in 100 cc. water). To the cooled solution, diethyl sulfate (30.8 g. or 27 cc.) was added and then sufficient alcohol (60 cc.) 30 to make the mixture homogeneous. It was allowed to stand for three days, after which a slightly acidified test portion of the reaction mixture gave no coloration with ferric chloride solution. Sufficient strong sodium hydroxide solution was added to give a strongly alkaline reaction and the mixture was treated under reflux for 1/2

35 hour, after which it was cooled and acidified. The crude dry product was recrystallized from benzene-alcohol (50:50 mixture; approximately 100 cc.) and gave shiny plates, M. P. 198° C.; yield, 11 g.

Stage (b).—*p-Ethoxybenzoyl chloride.*—p-Ethoxybenzoic acid (4 g.) prepared as above was

heated under reflux with thionyl chloride (4 g.) in benzene (20 cc.) until there was no further loss of hydrogen chloride. The benzene was re-

moved and the residue, which rapidly solidified while still hot, was kept over caustic soda to remove traces of thionyl chloride. Without further

purification the product was used in the next stage.

Stage (c).—*Compound C.*—4:4'-diaminostil-

bene-disulfonic acid (4 g.) in water (64 cc.) was just neutralized at the boil with sodium carbon-

ate. To the hot solution, p-ethoxybenzoyl chloride (4.4 g.) in pyridine (10 cc.) was added all at once. The product was worked up in the usual fashion and finally crystallized from aqueous pyridine. It was obtained as a pale yellow micro-crystalline powder. Yield 2 g. (30%).

The other compounds may be prepared in an analogous manner, using the appropriately substituted benzoyl chloride; i. e., for Compound B, the orthomethoxybenzoylchloride, for Compound D, the paramethoxy-meta-methylbenzoylchloride, for Compound E, the para-methoxy-meta-nitrobenzoylchloride (with reduction and acetylation of the resulting compound), and Compound F, the meta-para-dimethoxybenzoylchloride.

The following examples illustrate various applications of the invention. The particular compound used for imparting blue-fluorescent effects to the materials treated in these examples was the sodium salt of 4:4'-di-p-methoxybenzoylaminostilbene-2:2'-disulfonic acid (Compound A).

EXAMPLE I

Undyed bleached cotton yarn was treated in an aqueous bath containing 0.14% of sodium sulfate and 0.005% of the blue-fluorescent compound. The treated yarn after rinsing and drying had a brilliant white appearance in daylight, and showed strong blue fluorescence when illuminated by ultra-violet light and remained strongly fluorescent after long exposure to daylight and ultra-violet light.

EXAMPLE II

A new white cotton cloth was rinsed for a few minutes in an aqueous bath containing 0.005% of the blue-fluorescent compound. The treated cloth after drying and ironing showed a brilliant white appearance in daylight, which was not affected when the cloth was subsequently treated with a dilute solution of hypochlorite.

EXAMPLE III

A white cotton cloth was washed in a wash liquor containing 0.6% by weight of a soap powder itself containing 0.015% by weight of the blue-fluorescent compound. After rinsing, drying and ironing, the cloth showed a blue fluorescence when illuminated by ultra-violet light and a brilliant white appearance when illuminated by daylight.

All the foregoing compounds have been tested in the foregoing manner and give satisfactory results. Good results are also obtained in washing soiled cotton cloths with a wash liquid containing soap powder and the blue-fluorescent compound, in a manner similar to the foregoing; even in the first washing, and the effect improves with subsequent washings.

The requisite amounts of aminostilbene compounds in the washing liquor or in the preliminary laundering treatment may vary within wide limits. In general, it is preferred to express this in terms of the amount of textile to be treated, and usually not over about 0.01% is necessary, based on the dry weight of the textile material to be washed. Proportions ranging from 0.025 to 0.0001% have been found sufficient to impart an appreciable whitening effect. There is no advantage in using more than is necessary to obtain the white effect and, of course, the amounts used should be less than sufficient to impart a colored effect thereto. The amount need not be larger than 0.05%, based on the textile material to achieve a satisfactory whitening effect.

However, since the use of excessive quantities of blue-fluorescent substances does not in general produce over-blueing, which is an objectionable feature of the commonly used blueing agents, higher amounts, say up to one per cent or more, may be used without detriment to the effect produced. Such higher amounts, however, usually serve no useful purpose once the quantity producing maximum whitening effect for a given case has been reached.

If the detergent composition contains 0.01 to 0.075% by weight of the aminostilbene compound and the washing liquor contains 0.25 to 0.75% by weight of the detergent composition, the concentration in the liquor of the aminostilbene compound can be readily calculated.

The compounds of the present invention are particularly suitable for use in starch preparations for imparting fluorescent effects to materials such as textiles and the like.

EXAMPLE IV

A solution was prepared containing 200 cc. of water, 0.01 g. of the blue-fluorescent compound used in the preceding examples and 1 g. of sodium sulfate. 20 g. of good quality maize starch was suspended in this solution at 40° C. for 30 minutes, filtered off and dried at 40° C. The treated starch was very much whiter than the original starch. An improvement in the whiteness of starch was also obtained by using only one-tenth of the above quantity of the compound in a similar manner.

A starch whitened in the above manner was found capable of imparting a whitening effect to textile materials when used to starch the materials according to usual domestic laundering practice. For such laundering purposes, it is found that the starch would preferably be treated in the above manner with from 0.03% to 0.3% of the compound calculated on the weight of the starch.

EXAMPLE V

A new white cotton cloth was treated with an aqueous solution containing 0.01% of the blue-fluorescent substance used in the preceding examples and 0.004% of ultramarine. A brilliant white appearance was imparted to the cloth, which was considered by some observers to be preferable in tone to that obtained by the use of the blue-fluorescent substance alone.

It will be realized that a preparation can be made, in accordance with the invention, comprising a blue-fluorescent substance of the general formula mentioned above, and a blueing agent, that is a blue-coloured substance such as is used in the normal blueing treatment for washed textile articles. Such a preparation may also contain starch, and any fillers and other substances such as are incorporated in blueing agents.

In this connection, it may be mentioned that to a certain extent whiteness is a subjective impression of the observer. Shades of white exist, for example a bluish white, a greenish white or a pinkish white; and while one observer may consider a bluish white to be the whiter of samples of the three shades, another observer may prefer the greener shade. The incorporation of a small amount of coloured substance with the blue-fluorescent compound enables any desired shade of white to be given to the material to which the blue-fluorescence is imparted, and any suitable coloured substance or dye may be so in-

corporated. Thus the mixture of a blue-fluorescent substance and a suitable dye or pigment in the requisite proportions, together with any filling agents may be formed into a useful preparation for the purposes of the invention.

EXAMPLE VI

A transparent sheet of regenerated cellulose of the type commercially used as wrapping material was immersed in an aqueous bath containing 0.1% of the blue-fluorescent compound dissolved in a liquid consisting of 94 parts water and 6 parts glycerine. The sheet after drying possessed the property of absorbing ultra-violet light and this property was not noticeably impaired by prolonged exposure of the sheet to air and light. Transparent sheet material treated in this way can therefore be used with advantage for wrapping foodstuffs or other commodities which are sensitive to light and which are kept in storage or exhibited on shop counters or in shop windows for long periods of time.

The compounds of the present invention may usefully be incorporated in detergents, in any form such as bars, tablets, powders, flakes. The incorporation in soap powder has already been mentioned above in Example III. In this way a detergent is provided which simultaneously washes and whitens materials to which it is applied.

The detergents that are used with the stilbene compound are of the kind suitable for and customarily used in textile laundry practice. Suitable detergents generally are of the organic detergent type. Soaps form one large group of organic detergents. Another large group of organic detergents consists of surface-active compounds which consist of a combination of a hy-

drophylic group with a lipophilic group which may be any fairly long chain (usually aliphatic but sometimes mixed aliphatic-aromatic), with or without unsaturated or substituted groups. These include sulfonated oils such as the Turkey red oil of commerce, alkyl sulfates such as sodium lauryl sulfate (Gardinol); aliphatic sulfonates such as the condensation product of oleoyl chloride with the sodium salt of isethionic acid (Igepon A), the condensation product of oleoyl chloride with the sodium salt of taurine (Igepon T), diethyl sodium sulfosuccinate, alkyl aryl sulfonates such as the sodium salt of an alkyl benzene or naphthalene sulfonate acid wherein the alkyl group contains about 8 to 18 carbon atoms (Nacconol), Twitchell reagents, quaternary ammonium compounds such as cetyl trimethyl ammonium chloride, partial esters of polyhydric alcohols, such as mono stearin sodium sulfo acetate, sodium glyceryl monolaurate sulfate (Syntex M), dioctyl sodium sulfosuccinate (Aerosol OT), sapamines, pentaerythritol monostearate (Pentamul 6), polyglycol esters, and the like (as are known in the art, for instance, Bailey, "Industrial Oil and Fat Products," Interscience Publishers, Inc., New York, N. Y., 1945, chapter XII; and Dean, "Utilization of Fats," Chemical Publishing Company of New York, Inc., New York, N. Y., 1938, chapter IX, part 5).

While the above described compounds are included as illustrative embodiments of a preferred

mode of practicing the invention, other compounds are those of the general formula

in which each R and R₁ is a hydrocarbon radical, such as alkyl, aryl, or aralkyl, lower alkyl of from 1 to 4 carbon atoms being preferred; each x and x₁ being zero or a small integer such as 1, 2 or 3, or the like; each n, n₁, m and m₁ being integers expressing the number of the respective groups substituted in the respective benzene rings, such as 1, 2, 3, and the like (the maximum number being the positions on the benzene rings which are not otherwise substituted); each B being hydrogen or a cation such as sodium, potassium, ammonium, or the like; and each A and A₁ being hydrogen or a substituent such as methyl, acetyl-amino, and the like groups; but the compounds must not contain any free (primary) amino groups directly attached to any benzene ring, since the presence of such groups renders the compounds unstable to light, air and oxygen. Any of the benzene rings may contain substituents (except as specified above), such as methyl, acetyl-amino, and the like. Salts, such as sodium salt, are most convenient to use in practice.

A typical compound wherein m is 3 and m₁ is 3 is the following:

Sodium 4:4'-di-3':4"5"-trimethoxybenzoyl-aminostilbene-2:2'-disulfonate:

This compound may be prepared as discussed hereinbefore, using 3,4,5-trimethoxybenzoylchloride as the reagent to introduce the appropriately substituted benzoyl group. A compound in which x and x₁ are each 1 is sodium-4:4'-di-p-methoxybenzoylaminobenzoylaminostilbene-2:2'-disulfonate:

The other compounds within the broad formula may likewise be prepared using analogous reagents containing the appropriate substituents.

In the textile industry the compounds have use in their application to piece goods, yarns, fibre, fabrics and articles such as shirts, towels, sheets and the like made therefrom. Such materials may be treated with a dilute aqueous solution of the substance, which becomes attached to the material, giving it a brilliant white appearance, which, owing to the substantive properties of the substance, will remain through many normal washing and rinsing operations, thus removing the necessity for special "blueing" or whitening treatments each time the material is laundered.

Among other useful applications of the inven-

tion may be mentioned the preparation of fluorescent inks for marking textile fabrics to be cleaned or laundered with identification marks which are normally invisible but strongly fluorescent in ultra-violet light. It is clearly essential that such identification marks withstand customary laundering treatments and in particular do not become discolored when, for example, hypochlorite is used in the wash or the fabrics are dried in the sun, since any discoloration would obviously be highly detrimental. Identification marks produced by means of the blue-fluorescent compounds according to the invention remain practically unaffected by normal laundering operations.

The invention is not limited to the applications specifically referred to in this specification, but is useful for any purpose to which light-stable, blue-fluorescent substances may be applied, except as is not within the scope of the appended claims.

We claim:

1. A compound of the formula

where each B is a member of the group consisting of hydrogen, sodium, potassium and ammonium, where each x is selected from the group consisting of 0 and 1, where each A is a member of the group consisting of hydrogen, methyl and acetyl amino, where each R is an alkyl radical of 1 to 4 carbon atoms, and where each m is an integer selected from the group consisting of 1, 2 and 3.

2. A compound of the formula

3. A compound of the formula:

4. A compound of the formula:

5. A compound of the formula:

6. A compound of the formula:

7. A composition consisting essentially of a detergent comprising an organic detergent and not more than about 0.075% by weight of a compound of claim 1.

8. A composition consisting essentially of a detergent comprising an organic detergent and not more than about 0.075% by weight of the compound of claim 2.

9. A composition consisting essentially of a

detergent comprising an organic detergent and not more than about 0.075% by weight of the compound of claim 3.

10. A composition consisting essentially of a detergent comprising an organic detergent and not more than about 0.075% by weight of the compound of claim 4.

11. A composition consisting essentially of a detergent comprising an organic detergent and not more than about 0.075% by weight of the compound of claim 5.

12. A composition consisting essentially of a detergent comprising an organic detergent and not more than about 0.075% by weight of the compound of claim 6.

13. A method of laundering textile material which comprises washing said material with an aqueous solution comprising water and a detergent composition consisting essentially of a detergent comprising an organic detergent and about 0.01% to about 0.075% by weight of a compound of claim 1.

14. A method of laundering textile material which comprises washing said material with an aqueous solution comprising water and a detergent composition consisting essentially of a detergent comprising an organic detergent and about 0.01% to about 0.075% by weight of a compound of claim 2.

15. A method of laundering textile material which comprises washing said material with an aqueous solution comprising water and a detergent composition consisting essentially of a detergent comprising an organic detergent and about 0.01% to about 0.075% by weight of a compound of claim 3.

16. A method of laundering textile material which comprises washing said material with an aqueous solution comprising water and a detergent composition consisting essentially of a detergent comprising an organic detergent and about

0.01% to about 0.075% by weight of a compound of claim 4.

17. A method of laundering textile material which comprises washing said material with an aqueous solution comprising water and a detergent composition consisting essentially of a detergent comprising an organic detergent and about

0.01% to about 0.075% by weight of a compound of claim 5.

18. A method of laundering textile material which comprises washing said material with an aqueous solution comprising water and a detergent composition consisting essentially of a detergent comprising an organic detergent and about

11

0.01% to about 0.075% by weight of a compound of claim 6.

19. A method of imparting blue-fluorescent effects to materials which comprises immersing said materials in an aqueous solution containing from about 0.001% to about 0.05% by weight calculated on the basis of the weight of the dry materials treated of a compound of claim 1, removing said materials from said solution and drying said materials.

20. Fibrous cellulosic material having incorporated therein about 0.001% to about 0.05% by weight of a compound of claim 1.
